(57) **CLAIM**

The ornamental design for a controller sunshade, as shown and described.

DESCRIPTION

FIG. 1 is a front perspective view of a controller sunshade, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a rear perspective view thereof.

The broken lines immediately adjacent to the shaded surfaces depict the bounds of the claimed design, whereas all other broken lines depict portions of the controller sunshade which form no part of the claimed design.

1 Claim, 8 Drawing Sheets
